UNITED STATES PATENT OFFICE

137,977

DESIGN FOR A FOOD CONVEYER

Roy J. Baunach, Toledo, Ohio, assignor to The Swartzbaugh Manufacturing Company, Toledo,
Ohio, a corporation of Ohio

Application March 13, 1944, Serial No. 112,879

Term of patent 14 years

(Cl. D33—19)

To all whom it may concern:

Be it known that I, Roy J. Baunach, a citizen of the United States and resident of Toledo, in the county of Lucas and State of Ohio, have invented a new, original, and ornamental Design for a Food Conveyer, of which the following is a specification, reference being had to the accompanying drawing, forming a part thereof.

In the drawing: Fig. 1 is a perspective view of a food conveyer, showing my design; Fig. 2 is a similar view with the covers, drawers and doors in open position; and Fig. 3 is a top plan view of the conveyer in closed form.

I claim:

The ornamental design for a food conveyer, substantially as shown and described.

ROY J. BAUNACH.
